UNITED STATES PATENT OFFICE.

OSCAR F. BOOMER AND HENRY R. RANDALL, OF BROOKLYN, NEW YORK.

APPARATUS FOR MAKING VINEGAR.

SPECIFICATION forming part of Letters Patent No. 236,764, dated January 18, 1881.

Application filed November 6, 1880. (No model.)

To all whom it may concern:

Be it known that we, OSCAR F. BOOMER and HENRY R. RANDALL, both citizens of the United States, residing at Brooklyn, in the 5 county of Kings and State of New York, have invented new and useful Improvements in Vinegar-Making Apparatus, of which the following is a specification.

This invention relates to an apparatus for 10 the conversion of a suitable liquid into vinegar by exposure to air. Its object is to provide, in a small space, a great extent of surface over which the liquid must flow, be exposed to the air, and brought in contact with 15 vinegar ferment or spores.

It consists in the arrangement, in a vinegar apparatus, of one or more series of shelves covered with cloth or other fibrous material, one above another in such position that a liquid 20 will flow from one shelf to the next lower after traversing the threads of the cloth or fibrous covering, a portion of said liquid, and of the vinegar ferment or spores being retained in the meshes of the cloth or other fibrous material, and inducing a speedy fermentation in 25 fresh liquid coming in contact therewith and with the air, as hereinafter more particularly described with reference to the accompanying drawings, in which—

30 Figure 1 is a vertical section of an apparatus constructed according to our invention. Fig. 2 is a horizontal section on line x x of Fig. 1; and Fig. 3 is a detail view of one of the shelves surrounded by a cloth covering.

35 The letter A designates a box or chest, which may be of any desired size, and preferably rectangular in shape. Within this box or chest are arranged several vertical series of shelves B, extending between and having their 40 ends secured to the side walls. These shelves are slightly curved transversely on top, and the several series are separated by suitable spaces. From the bottom of each shelf projects a longitudinal rib, C, preferably triangular in cross-section, and each shelf, with

its rib, is surrounded by a covering, D, of cloth or other fibrous material, fitting closely upon its curved top, but held away from its under surface by the rib, so that two converging cloth surfaces meet at an angle under each 50 shelf, this angle being directly above the longitudinal center of the top of the next lower shelf and at a little distance therefrom. Near the top and bottom of the chest suitable air-holes G are formed in its walls to permit a 55 proper supply of air to enter; but we may cause a downward flow of air through the chest by means of a suitable blower, as shown at H, the lower air-holes in the wall of the chest being closed when the blower is connected to the bottom of said chest, as shown, and vice versa.

When the liquid is fed from a suitable source into the troughs F it trickles through the slits or openings in the top of the chest, falls upon 65 the tops of the top shelves, and flows sidewise in both directions until the fibrous coverings are thoroughly saturated, when it trickles off at the angles under the shelves and falls upon those below, this action continuing until it 70 finally reaches the lowest angles and drops into the tank. During its passage a portion of the ferment or spores is retained in the meshes of the cloth or other fibrous covering, and induces a rapid fermentation of fresh liquid, which 75 comes in contact with it and the air in the chest while making its way downward over the shelves and coverings.

We are aware that in vinegar-making apparatus cloth has been used to cover a filtering shelf, and that the liquid has been caused to traverse a series of shelves, falling from one to another; and we do not claim, broadly, the cloth-covered shelf, nor an apparatus provided with a vertical series of shelves to be traversed 85 by the liquid.

What we claim is—

1. In a vinegar-making apparatus, one or more series of shelves covered with cloth or other fibrous material, and arranged one above 90

another in such manner that the liquid will fall from one shelf, after traversing it and its covering, upon the next lower, and traverse it and its covering in a like manner, substantially as described, and for the purpose set forth.

2. The combination, with one or more series of shelves, B, provided with the ribs C, of the cloth coverings D, forming downward projections under the shelves, substantially as and for the purpose set forth.

In testimony whereof we have hereunto set

our hands and seals in the presence of two subscribing witnesses.
